B. C. Bromwell, of Skowhegan, Me.
assor. to

himself S. D. Greenleaf, C. J. Douglass,

and R. C. Douglass, of same place.

Letters Patent No 1732, dated Mch. 10. 1863.

The schedule referred to in these Letters Patent and making part of the same.

To all whom it may concern:

Be it known that I, B. C. Bromwell, of Skowhegan, in the County of Somerset, and State of Maine, have invented or produced a new and original Design for a Pump; and I do hereby declare that the following is a full, clear and exact description of the same, reference being had to the accompanying drawings, making a part of this specification, in which.

Figures 1, and 2, are elevations of a pump, showing my design.

Figure 3, a horizontal section of the same, taken in the line x, x, Figure 1.

Similar letters of reference indicate corresponding parts in the several Figures.

This design relates to an upright cast metal pump of which A, is the cylinder, the upper and lower parts a, a, of which have a smooth exterior. The central part b, of the cylinder is less in diameter than the parts a, a, so that a space or shoulder is allowed at the inner ends of a, a, for an ovoli bead c.

The central part b, of the cylinder A, has a series of horizontal ring projections d, upon it, as shown in Figures 1, and 2, B, is a suction tube which adjoins the cylinder A, has a smooth exterior and is of cylindrical form except at its lower part e, which is conical see Figure 1. The upper end f, of the tube B, where it communicates with the cylinder A, is curved.

C, is the education tube of the pump, shown in red outline in Figure 2. This tube C, communicates with the upper and lower parts a, a, of the cylinder by means of horizontal pipes g, g. It forms no part of the design.

Having thus described my invention, what I claim as new and desire to secure by Letters Patent, is

The configuration of the cyl.

inder A, and suction pipe B, as herein shown and described to form a new and original design for a pump.
